UNITED STATES PATENT OFFICE.

CARLETON ELLIS, OF MONTCLAIR, NEW JERSEY.

PROCESS AND APPARATUS FOR HYDROGENATION.

Application filed November 25, 1918. Serial No. 264,005.

To all whom it may concern:

Be it known that I, CARLETON ELLIS, a citizen of the United States of America, residing at Montclair, in the county of Essex and State of New Jersey, have invented certain new and useful Improvements in Processes and Apparatus for Hydrogenation, of which the following is a specification.

This invention relates to the hydrogenation of oils and has especial reference to the agitation and circulation of the oil effected either wholly or partially by the hydrogen gas introduced, and comprises a novel method and apparatus, by means of which the agitation of the oil is effected in an efficient manner.

In the art of hydrogenation of oil, various types of apparatus have been proposed. The prior processes which are based on forcing hydrogen through a body of oil all leave something to be desired in regard to the circulation or mixing of the body of oil, especially when large units are employed. Mechanical stirring is resorted to in many cases, but is open to the disadvantage of liability to allow leakage. Such stirring is useful in a preliminary way, when used in stirring and mixing the oil while the same is being brought up to the hydrogenation temperature, when the hydrogenating receptacle is used for such heating purposes.

According to present practice, the hydrogenation is usually carried out in vertical tanks, with or without mechanical stirrers, hydrogen being blown in at the bottom. Such apparatus may be used successfully with units of a few hundred, or even a few thousand pounds capacity, but with units of say, ten to twenty thousand pounds or more, especially when the flow of gas through the liquid is relied upon to secure proper contact between the reacting components, irregular flow of the gas and consequent eddies tend to cause deposition of the catalyst, or in other words, to prevent most effective contact of the gas with the catalytic material.

If the depth of the oil is increased in order to secure large capacity, objectionably high pressures of hydrogen gas are needful. If a shallow, broad tank is employed, the trouble from pocketing is greatly aggravated.

Vertical tanks with conical or inverted pyramid-shaped bottoms provided with a hydrogen inlet located at the apex of the

cone or pyramid, have the disadvantage of giving such a restricted degree of circulation in the lower part, owing to its restricted cross-section, as not to be entirely satisfactory.

It is much to be desired to provide a receptacle of a capacity of, say, ten to fifteen or twenty thousand pounds or more, which will be cheap, simple of construction, easily accessible, capable of exact temperature control, and above all, one in which the circulation of the oil and movement of the catalyst, when finely divided, follows definite paths capable of giving the greatest hydrogen-absorbing effect, without objectionable deposition of catalyst on the bottom of the tank, or if the catalyst does so deposit, will throw it again into suspension in the oil under treatment.

The present invention seeks to achieve the foregoing desirable results by giving to the body of oil such a shape that the hydrogen being introduced, preferably at or near the bottom of such body of oil, produces continuous currents in the body of oil, thereby effecting a mixing of the oil and causing the catalyst to be more or less uniformly distributed or disseminated in the oil. It is preferred also by so shaping the container, and hence the bottom of the body of the oil, that any of the catalyst which drops out of the oil will gradually work its way toward the hydrogen inlet, so as to again be distributed in the body of oil.

Apparatus within the scope of my invention is illustrated in the accompanying drawings, in which Fig. 1 shows a vertical longitudinal section of an apparatus coming within the scope of the invention, and Fig. 2 shows a cross-section of the same, intermediate the ends thereof, and Fig. 3 shows a preferred form of hydrogen inlet pipe or distributor for use in the apparatus of the two figures referred to above, which distributor is also suitable for use with several of the other figures described below. Fig. 4 is a cross-section of another tank, showing a different arrangement of the heating coils. Figs. 5 and 6 show respectively a cross-section and a longitudinal section of another form of apparatus embodied within the present invention, this apparatus being particularly suited for continuous operation, and showing a modified form of hydrogen inlet and also showing baffle plates arranged in such a manner as to aid the circulation

and mixing of the oil. Fig. 7 is a cross-section of still another modification of the apparatus, this figure showing a V-shaped trough with a vertical row of heating pipes placed above the hydrogen inlet. Fig. 8 shows, partly in longitudinal section and partly in elevation, and Fig. 9 shows in vertical cross-section, another form of apparatus in which the unabsorbed gas removed from the gas exit of the oil treating vessel may be cooled, purified, re-heated and returned to the oil treating receptacle. These forms of apparatus are intended to be illustrative of the many forms of apparatus coming within the scope of the present invention.

Referring more particularly to the drawings, 1 represents a tank, which is preferably elongated and which may be cylindrical as illustrated in Figs. 1 and 2, the length of the tank being preferably considerably greater than its diameter. Thus, tanks having a length equal to one and one-half times the diameter up to ten or more times the diameter may be found efficient, depending upon the particular conditions under which it is desired to operate. The hydrogen distributing pipe is preferably located at or near the bottom of the tank, so that the hydrogen introduced through the inlet pipe will rise, causing a flow of oil and catalyzer in the direction of the arrows, as illustrated in the various figures. The tank may be provided with suitable heating means in Figs. 1 and 2, heating coils 2 being shown for this purpose, which coils may be arranged in such a manner as to form a sort of baffle on each side of the hydrogen inlet pipe, so that the oil carrying the finely divided catalyzer will be raised in the central portion of the tank, and will drop down outside of the baffle shaped coils, as shown particularly in Fig. 2. The hydrogen introducing means together is represented by the numeral 3.

4 represents a supply of hydrogen to the distributor 3. 5 represents a pump through which the unabsorbed hydrogen collecting in the upper part of the tank 1, or in a dome 7, may be drawn through pipe 6, and passed by pipe 8, pipe 4 and distributor 3 into the mixture of oil and catalyzer. Other pipe connections, such as an additional draw-off pipe 9, or an additional draw-off pipe 10, may be provided, also a pipe 11, and a pipe 12 for additional hydrogen supply may be provided. 13 is the valve in the pipe through which the oil or mixture of oil and finely divided catalyzer may be introduced into the tank, either at normal temperature or in a preheated condition. 14 is a valve in the draw-off pipe, by means of which the oil at the end of the operation may be drawn off. A suitable thermometer 15 and a suitable test cock 16 may also be provided at any suitable place in the tank,

preferably below the normal liquid level therein. The hydrogen inlet device 3 may consist of the device illustrated in Fig. 3, namely, a branched pipe, one branch of which, 17, is straight, and one-half of the length of this is provided with numerous small perforations, as illustrated, and the other half, 18, is bent and a portion of the length of this is likewise provided with numerous small perforations. The perforations may be in the top of the distributor or if desired, the distributor may be turned over as shown in Fig. 1 so that the perforations are in the bottom of this.

Fig. 4 illustrates a cross-section of a cylindrical tank of any desired length in which the process may be carried out. This tank is provided with a hydrogen inlet 23, which may be a long pipe running substantially the entire length of the tank and provided both in its top and in its bottom with a large number of small holes through which the hydrogen enters the oil. In the upper part of this tank and substantially above the hydrogen inlet may be located a heating element composed of a coil 22, the number of pipes in each course of which is successively smaller working downward so that bunch of pipes collectively acts as a baffle to cause the separation to a certain extent of the oil passing to the right of this coil from the oil passing to the left of this coil.

In Figs. 5 and 6 I have shown a trough shaped hydrogenation vessel 25 provided with a temperature regulating jacket 26. In a vessel of this character suitable baffle plates 28 and 29 may be provided to aid the circulation. In these figures, I have shown a different variety of a hydrogen inlet device consisting essentially of an imperforate pipe 30 located close to the bottom of the baffle 29 and connected by means of short pipes 31 with suitable short sections of perforated pipe 32, the ends of which are preferably plugged. In this form of apparatus the mixture of oil and catalyzer travels in the direction indicated by the arrows, and the mixture of oil and catalyzer may be introduced through the pipe 33, and may leave the apparatus through the pipe 34, already hardened to the desired extent. Of course, in the commencement of the operation in an apparatus such as shown in Figs. 5 and 6, the oil may be drawn off and circulated through the apparatus, or the entire bulk of oil in the apparatus at the commencement of the operation may be allowed to stand therein without any oil being drawn off until a sufficient amount of hardening has been effected in this oil.

In Fig. 7 I have shown a still different modification, this consisting essentially of a trough of substantially V-shape cross-section, having a hydrogen inlet 37 at the lower end thereof, that is to say, in the apex of the

V, and located substantially above this hydrogen inlet I may provide a vertical row of temperature regulating pipe 38, which also, to some extent, act as baffles. The 5 trough or tank is provided with a top 39 which may be curved, as illustrated, or flat if desired, and in the latter case, a suitable dome would be provided at some point in the length of the trough.

10 In the forms of apparatus as described above, the unabsorbed hydrogen can be drawn off from the top of the tanks and used for any desired purpose. In Figs. 8 and 9, I have shown respectively a vertical 15 elevation partly in section of an oil treating receptacle coming within the scope of the invention and a cross-section of the same. It is frequently desired to draw off the hydrogen, which has escaped absorption, and 20 to subsequently reintroduce this into the lower part of the tank or hydrogenation receptacle.

25 In the device shown in Figs. 8 and 9 of the drawings, 41 is a horizontal cylindrical tank, the upper part of which is shown in longitudinal elevation and the lower part is shown in longitudinal section, 42 is a coil arranged for the admission of steam or hot oil for heating the contents of the tank, as 30 may be desired, and also for cooling purposes by the circulation of cold water or other cooling agent therethrough, when the temperature rises beyond the desired point due to exothermic reactions taking place in 35 the oil during the hydrogenation process.

43 is one form of an inlet pipe or distributor for hydrogen gas which may be in the form of a single perforated pipe as shown or preferably when using tanks of 40 considerable length may be formed of a number of pipes terminating at different points in the bottom of the hydrogenating tank, each terminus being equipped with a nose or similar device so that the entire body 45 of oil is thoroughly stirred by the fairly uniform introduction of the hydrogen gas thereinto. 44 is a dome for collecting unabsorbed gases. 45 is a blow-off pipe fitted with a valve, through which the unabsorbed 50 gas may be allowed to escape if very impure, for example, at the commencement of the hydrogenation process, when a considerable quantity of steam or other impurities may be present in the gas. 46 is a tank fitted with an agitator, the driving pulley 55 of which is shown at 47; in which tank the oil and catalyst are mixed and are run therefrom by the pipe 48 into the treating tank 41. The pipe 49 leads from the top of 60 the dome 44 and may communicate with either one of the pipes 50 or 55 by proper manipulation of the valves. The pipe 50 communicates directly with the pump 52. The pipe 55 serves to connect the pipe 49 65 with the heat exchanger 54, whereby the hot

outlet gases heat the incoming hydrogen. The outlet from the pump 52 may communicate with the regenerator or heat exchanger, by the pipe 53. The pipe 56 extends to the purifiers 57, 58 and 59 and from the latter the pipe 60 communicates with the regenerator 54. The pipe 100, through which the hydrogen is fed to the inlet 43, may be otherwise heated, e. g., by immersing the same in a bath of hot oil, so that the hydrogen will enter the oil in 41 at about the same temperature as said oil. Intermediate the ends of the pipe 60 is a pump 61 which may be of the positive pressure type as indicated or may be a steam pump similar to that shown at 52. In place of using a steam pump, such as the pump 52, a positive pressure blower likewise may be used at that point. The regenerator 54 consists of a shell or cylindrical chamber enclosing the pipe, or nest of pipes, or pipe coil through which the cold hydrogen from pipe 60 is about to enter the treating tank 41. The hot unabsorbed hydrogen is allowed to blow through the space between this pipe and the cylindrical jacket thereby heating the gas about to enter the tank 41. Additional pure hydrogen is admitted through pipe 63, as desired.

90 The purifiers are filled with suitable absorbing agents, such as caustic soda solution or lumps of dry caustic soda or soda lime and the like. A solution of caustic soda may be used in the tank 57, a solution of permanganate of potash may be in the tank 58, and the tank 59 may contain calcium chloride or soda lime for drying purposes. A considerable amount of water is removed from the oil by the hydrogen gas and this, together with other impurities 95 taken up by the unabsorbed hydrogen should be eliminated to a large extent before the unused hydrogen is returned to the oil by the cyclic flow.

100 A layer of oil is placed in the tank 41, which layer may be of any desired depth, but preferably completely covering the coils, and into this oil the requisite amount of catalytic material, such as finely-divided nickel, is introduced, or the mixture of oil 105 and finely-divided catalyst is run into the tank from the tank 46. The catalyst is preferably very finely divided so that the gas circulation will maintain the catalyst in suspension in the oil under treatment. The 110 layer of oil may be about two to four feet in thickness, in order to secure the best results of the hydrogen treatment. Under these circumstances, a comparatively low hydrogen head or pressure is sufficient to maintain the rapid hydrogen current through the oil so that hydrogenation takes place quickly and effectively and without difficulties attendant on the use of strong 115 pressures of hydrogen. During the first 120

hour or so that the oil is being treated with hydrogen, water (in the form of vapor) and other products are formed in considerable amount and a considerable proportion of the hydrogen gas is shunted through the purifiers 57, 58 and 59, or may be allowed to go to waste, or led off for use as fuel through pipe 45. The circulated gas is cooled before and during the purification, and on its return is passed through the regenerator 54, thereby heating it up to about the requisite temperature. Thus hot, instead of cold, hydrogen enters the body of oil and this heating is especially desirable when hydrogenating shallow layers of oil, because hydrogen is a poor conductor of heat, and when traveling as a strong current through a body of the oil may well pass entirely through the oil without becoming heated sufficiently to react readily.

In all of the forms of apparatus illustrated and above described the current of hydrogen entering near the bottom of the body of oil produces an efficient circulation or mixing, and the catalyzer, which is preferably finely divided, is maintained in suspension in the oil. Any catalyzer which may settle out of the oil during this circulation tends to fall onto the bottom of the receptacle and works its way toward the hydrogen inlet to be again brought into suspension in the body of oil under treatment, by the hydrogen gas introduced.

In all of the forms of apparatus illustrated the heating elements or coils may be used in the commencement of the operation for heating the oil to the desired temperature, say, about 180° C., and thereafter the heating agent to the heating coils or elements may be cut off, and subsequently the temperature of the oil may rise somewhat, due to the exothermic reaction taking place between the hydrogen and the oil. Accordingly, it will be advisable during the later stage of the operation, in order to prevent injury to the oil by overheating to pass a cooling agent through the said coils or jackets.

It will be understood that the present invention is suitable for use with catalyzers, which can be suspended in the oil, and this, of course, includes colloidal catalyzer, as well as catalyzer in the form of grains of larger size. When using a colloidal catalyzer, it is possible to employ flat bottomed tanks or treating receptacles, since under these conditions the catalyzer will remain suspended in the oil almost indefinitely.

The present application is in part a continuation of matter described in my copending application No. 75,769 filed February 2, 1916 (now Patent No. 1,294,068, February 11, 1919).

I claim:

1. In the hydrogenation of fatty oils con-

taining unsaturated constituents, the step of maintaining an elongated substantially horizontal body of such oil while causing a defined circulation therein in a vertical plane, such oil carrying in suspension therein a catalyst which carried about in the oil by currents of the oil, and introducing thereto, at a level well below the surface of such oil, at a plurality of points in the length of such body, a hydrogen-containing gas, while such oil is at a temperature at which such catalyst is capable of causing a union of hydrogen with constituents of such oil.

2. A process of hydrogenating oil which comprises introducing hydrogen at near the bottom of an elongated body of oil in which are placed baffle elements so arranged, as to cause a definite circulation of the oil past the hydrogen inlet, such oil carrying a loose pulverulent catalyzer maintained in suspension by currents produced in said oil, such baffle also being internally heated to heat the oil and to maintain the temperature necessary for the hydrogenation operation.

3. In the hydrogenation of fatty oils containing unsaturated constituents, the step of introducing hydrogen near the bottom of a horizontally elongated body of oil containing catalyst in suspension, such body of oil being substantially unobstructed as to vertical movement therein, the sides of such body of oil sloping toward the hydrogen inlet, whereby any of the catalyst which may settle out tends to work its way toward the said hydrogen inlet, and thereby bringing any catalyst which settles out of said oil back to positions near said hydrogen inlets; whereby the same tends to be again thrown into suspension in the said oil.

4. A process which comprises introducing hydrogen at a row of points located near the bottom of an elongated body of fatty oils, in which are located baffle elements so arranged as to cause a definite circulation of the oil past the hydrogen inlet, such oil carrying a loose pulverulent catalyzer maintained in suspension in the oil, by currents of the oil produced by such introduction of hydrogen, the baffle and the row of points of introduction of the hydrogen both being substantially parallel to the longitudinal axis of the body of oil under treatment, and maintaining the oil at the temperature necessary for hydrogenation.

5. An apparatus for hardening fatty oils and the like comprising a substantially horizontally arranged cylindrical receptacle adapted to contain oil and catalyzer, means for forcing a current of hydrogen-containing gas into the cylinder near the bottom and substantially beneath and parallel with the axis of the cylinder, temperature regulating coils within the cylinder spaced to either side of the axis of the cyl-

inder and also spaced away from the side walls thereof, whereby, when hydrogen is forced through a body of oil deep enough to cover said coils, the gas passes substantially 5 upwardly in the oil through the space between the coils and causes the oil and catalyst to move upwardly with the hydrogen and then downwardly substantially along the sides of the cylinder to the bottom 10 thereof.

6. An apparatus for hydrogenation comprising an elongated tank a perforated hydrogen inlet conduit located well below the normal liquid level and extending lengthwise of the tank, a pair of temperature regulating coils located one on each side of said inlet conduit and spaced apart to leave a substantially vertical substantially free passage in said tank, said vertical passage being in 15 the same vertical plane with said hydrogen inlet conduit, an oil inlet and an oil outlet to said tank, an outlet for unabsorbed hydrogen located above the normal oil level in the tank, and substantially free passages 20 between the spaces occupied by the said temperature-regulating coils and the sides of the tank, whereby a free circulation channel is provided for the oil to pass upwardly in the passage between the coils, horizontally 25 outwardly above the spaces occupied by the said coils, downwardly in the free passages outside said coils and inwardly toward the plane of the said hydrogen inlet in the free passages below the spaces occupied 30 by the said coils.

7. A horizontally arranged tank, a hydrogen inlet comprising a plurality of hydrogen inlet openings arranged substantially lengthwise of said tank, a pair of 40 heating coils spaced apart and located one on each side of the line of said hydrogen inlet openings, said coils being spaced away from the walls of the tank on all sides and being located entirely below the normal 45 liquid level in the tank.

8. An apparatus for hydrogenation comprising a horizontally arranged tank, a perforated hydrogen inlet extending lengthwise thereof and arranged in the lower part 50 thereof, a hydrogen outlet connected to the upper part of said tank, a chemical purifying apparatus a heat exchanger, and

means for carrying a flow of gas from the said hydrogen outlet through one section of the heat exchanger, through the purifying 55 apparatus, through the other section of the heat exchanger and back to the said hydrogen inlet and a connection for bringing further amounts of hydrogen into the cyclic gas path.

9. An apparatus for hydrogenating oil comprising a receptacle for treating oil, the greatest dimension of such receptacle being horizontal, such vessel being provided with an inlet communicating with a source of oil 65 to be treated, a hydrogen supply device located in the lower part of said tank, and provided with inlet openings throughout at least the major part of the length of said treating tank, and a vertically extending 70 baffle arranged in said tank.

10. In the hydrogenation of fatty oils containing unsaturated constituents, the step of introducing hydrogen near the bottom of a horizontally elongated body of oil 75 containing a catalyst in suspension, such body of oil being substantially unobstructed as to vertical movement therein, and, by the circulation of the oil, bringing any catalyst which settles out of said oil back into position near the point of entry of the hydrogen gas, whereby the catalyst which settles out of the oil tends to be again thrown into suspension in the said oil.

11. A horizontally arranged tank, gas inlets thereto arranged along the bottom of said tank throughout at least the greater part of the length thereof, baffles in said tank arranged lengthwise thereof and located on either side of said gas inlets, and 80 heating means for said tank.

12. A horizontally arranged tank, free from any such obstructing surfaces therein as would tend to prevent circulating currents through substantially the entire body 85 of such oil, a hydrogen inlet comprising a plurality of inlet openings arranged substantially lengthwise of said tank, and in the lower part thereof, and a vertically extending baffle forming a heating means for 100 said tank.

In testimony whereof I affix my signature.

CARLETON ELLIS.
